UNITED STATES PATENT OFFICE.

ANDREW ELIASON, OF DETROIT, MICHIGAN.

MAGAZINE TOOL HOLDER.

Application filed March 7, 1921. Serial No. 450,146.

To all whom it may concern:

Be it known that I, ANDREW ELIASON, a subject of the King of Sweden, residing at Detroit, in the county of Wayne and State 5 of Michigan, have invented certain new and useful Improvements in Magazine Tool Holders, of which the following is a specification, reference being had therein to the accompanying drawings.

10 This invention relates to improvements in tool holders, pertaining more particularly to structures of the magazine type although it is to be understood that while the invention contemplates a holder adapted to carry 15 a plurality of tools as a reserve to meet the various exigencies of use, the structure is not limited in this respect since it can be used in connection with a single tool.

15 The invention is especially adapted to use 20 in connection with screw driver blades or blanks, and for purposes of illustration, the invention is described in connection with this particular use.

25 The invention is designed to provide a construction of great strength and capable of exerting a maximum torsional pressure upon the screw being set or unscrewed without liability of damaging or straining the tool or its holder.

30 A further object is to provide a holder for the blade in such form as to permit of ready substitution of one blade for another also to permit of the use of blades in various positions. In addition, the invention 35 is designed to permit of the use of a blade of simple structure and capable of being manufactured at a relatively low cost and of such characteristics as permit of ready substitution of one blade for another.

40 A further object is to provide a construction which is simple and efficient in operation durable in construction, and which can be manufactured at a relatively low cost.

45 To these and other ends, the nature of which will be readily understood, as the invention is hereinafter disclosed, said invention consists in the improved construction and combination of parts hereinafter fully described, illustrated in the accompanying 50 drawings, and more particularly pointed out in the appended claims.

In the accompanying drawings, in which similar reference characters indicate similar parts, in each of the views,

55 Figure 1 is a central longitudinal sec-

tional view, with parts shown in elevation of a preferred embodiment of the invention;

Fig. 2 is a view in side elevation, with parts broken away, of the embodiment shown in Fig. 1, the blade being located at 60 a different position;

Fig. 3 is a transverse sectional view on the line III—III of Fig. 1;

Fig. 4 is a cross sectional view taken on the line IV—IV of Fig. 1; 65

Fig. 5 is a perspective view of one of the blades or tools;

Fig. 6 is a perspective view of a portion of a tool holder, in a form in which it may be used as a small screw driver; 70

Fig. 7 is a view in elevation, parts being broken away, showing a different way in which the holder can be utilized;

Fig. 8 is a transverse section taken through parts shown in Fig. 7. 75

The invention consists primarily in a hollow open ended member —a—, a tool carrying member —b—, having a shank —b'— detachably connected thereto, a cap —c— and blades —d—, the tool being preferably 80 completed by a small wrench of sheet metal adapted to permit of securing the removal of the shank or stem —b'— from the member —b—.

Member —a— has a body portion 15 85 which may, if desired, be fluted, as shown in Fig. 2, the body portion being provided with an internal washer-like member 16 which is secured within the body portion by suitable means, such for instance, as pins 90 17, member 16 serving to form the bottom of a chamber 18 within which the reserve tools are located, this chamber forming the magazine for the tool. Member 16 also serves as a stop to limit the inward movement of member —b— as presently described. 95

Member —a— beyond partitions 16 is preferably brought into a cross sectional area less than that of the body portion 15; 100 if the member —a— be of metal, this reduced portion, indicated at 19, may be drawn or otherwise produced. The portion 19 has an internal configuration which is of non-circular contour, the particular contour shown being that of a hexagon, although it will be readily understood that the particular form of the contour may be varied, as may be found desirable, the hexagonal form being a convenient form 105 110

and not requiring any special manipulation of member $-b-$ when the latter is being inserted.

The end of portion 19 is open, as is the end of portion 15, the latter being closed by the cap $-c-$ which forms the cover for the magazine, cap $-c-$ and body portion 15 having no threaded engagement, the cap being free to rotate relative to portion 15, being held in position by being threaded on to shank or stem $-b'$, as shown in Fig. 1.

In the embodiment shown, member $-b-$ is shown as a solid piece of material, excepting the slot presently referred to, this being a preferred arrangement, although the member may be changed in this respect, as for instance by being hollow. However, I prefer to form the member of stock material, thus giving the member the characteristic of a uniform cross sectional contour from end to end of the member, this contour being complementary to that of the interior of portion 19 of member $-a-$. Member $-b-$ has a length approximately equal to the distance between partition 16 and the open end of the portion 19, although the member may vary in length, the drawings showing the member as projecting slightly beyond the end of the portion 19.

Member $-b-$ and its shank or stem are preferably detachably connected together, the stem being in the form of a rod which is threaded at its opposite ends, the inner end being threaded into member $-b-$, the outer threaded end being adapted to be threaded to cap $-c-$. The connection between member or block $-b-$ and its stem is one that is not ordinarily disengaged, and hence it is desirable that the connection be made tight, and for this reason the stem may be provided with a flattened portion 20 which can be engaged by a suitable wrench for the purpose of tightening the stem into the block.

As will be seen member $-b-$ is held in proper position by cap $-c-$, the latter being threaded upon the thread end of stem $-b'$ and since the cap carries a flange which engages the end of body portion 15, it will be understood that rotative movement of the cap will serve to draw the member or block $-b-$ inward into contact with the partition 16, thus holding the parts firmly together. While member $-b-$ fits within portion 19 of member $-a-$ with a reasonably tight fit, the fit is sufficiently loose to permit outward movement of the member when permitted, by unscrewing cap $-c-$. And, in this connection, the particular arrangement of the cap and stem with the body portion 15 permits of a ready removal of member $-b-$, this result being readily had by giving cap $-c-$ a few revolutions, thus withdrawing the cap flange from contact with the head of the body portion 15, then striking the cap to drive its flange to

contact with the body portion 15, and thus project the advance end of member $-b-$. This operation is then repeated, thus projecting member $-b-$, by a progressive advancement, until the cap has been unthreaded. This projects member $-b-$ sufficiently to be grasped, or the end of the stem may be pushed inward to increase the projection until member $-b-$ has been removed. It will be understood, of course, that removal of member $-b-$ also carries with it stem $-b'$. When the member is being inserted, it can be pushed inward until the stem is in position where the threads of the cap may engage the threads of the stem after which a rotative movement of the cap will serve to draw the member to its housed position.

The blades $-d-$ are preferably made from flat stock, as for instance spring steel, these being generally of uniform thickness, excepting that the outer end is subjected to pressure so as to produce the working end of the blade, this particular portion being indicated at 21, the tool itself being designed to provide for the use of blades for different purposes. It will be readily understood that the thickness of portion 21 will depend upon the particular use which the blade is to have. For instance, one blade may have a portion comparatively thin, while another blade may have it of considerably greater thickness, these differences being designed to accommodate, for instance, screw heads of different sizes, and which have kerfs of different widths. And in this connection, it may be desirable to vary the width of the blades at the portion 21, Figs. 5 and 6 showing how this may be done.

The opposite end of the blade is preferably of a width approximating that of the thickness of member $-b-$ in one of its cross sectional dimensions, and this width extends for a portion of the length of the blades, so that when the blade is inserted within the member $-b-$ it will practically extend throughout this particular dimension and be held against movement in the direction of its transverse length, this result being attained by reason of the fact that this particular portion of the blade is then housed within the portion 19 of the member $-a-$.

Member $-b-$, which receives the blades $-d-$, is provided with a longitudinal slot or kerf 22 which extends inwardly from its outer end a desired distance. It may be readily formed by simply sawing or cutting the member with the saw cut extending across the axis of the member, the kerf having preferably the same width as the width of the blade, the arrangement being such that the blades will fit within the kerf without play, but permit of removal when desired.

To retain the blade in position, the blade

is provided with one or more—preferably two—projections 23 near its inner end, these being provided in a simple manner by the insertion of rivets, the heads of which project 5 above the plane of the sides of the blade. To receive these projections, I provide one or more enlargements 24 to the kerf or slot 22, this being provided by the use of a suitable drill or instrument having a diameter greater 10 than the width of kerf 22.

I have shown member —b— as having two of these enlargements, either of which can be employed by simply withdrawing member —b— from member —a— and then inserting 15 the blade into the slot in such position that the projections 23 pass into these enlargements. Since there are two projections 23 preferably employed, it will be readily understood that the blade when inserted will 20 be held from rocking movement. Generally the projections will be placed within the outer enlargements, as shown in Fig. 1, thus providing a considerable projection of the blade. However, in some classes of work it 25 may be desired to restrict the amount of projection of the blade so as to avoid springing or other difficulties in which case the projections 23 may enter the inner enlargements as shown in Fig. 2, the uniform thickness of 30 the blades and the uniform width of the slots permitting the blade to be properly inserted to provide either engagement. It may be desired to render the tool applicable for use under conditions where a leverage action 35 can be had, and for this reason I prefer to provide an additional enlargement 25 which extends along the axis of member —b— to the bottom of slot 22, enlargement 25 being designed to receive the projections 23 when 40 the blade is inserted with its length transverse to the length of member —b—, as shown for instance, in Fig. 7, the blade being inserted by movement in the direction of length of the member. If moved to the bottom of slot 22, and the free end of member 45 —b— then placed in the portion 19, as indicated in Fig. 7, member —a—, member —b— and stem —b'— provide a long handle which can be used for providing a long leverage or 50 purchase for manipulating the tool. This leverage can be produced at one end only if the member —b— be not re-inserted within member —a—. And, a comparatively short handle may be produced by removing stem 55 —b'—. And, if desired, member —b—, if stem —b'— be removed, can be employed for a small size screw driver, as shown for instance, in Fig. 6, the blades being inserted 60 within the transverse enlargements.

As will be seen, the particular arrangement of the parts is such as to permit of production in a simple manner and at low cost for labor, the member —a— being the more expensive part to be produced, this member, 65 however, being capable of production at a

comparatively low cost. The tool is of a form to be very powerful in action, since the simple form of the blades permits of the use of high grade steel, and the non-circular conformation of the contacting faces of 70 member —a— and —b— is such as to permit of maximum pressure being applied on the tool to produce the desired result without liability of damaging the tool. And since all of the blades can be readily carried with 75 in the magazine portion 15, it will be readily understood that the tool can be readily carried in a tool chest without taking up an excessive amount of room. As will be readily understood in comparing Figs. 1, 6 and 7, the 80 arrangement is such as to be applicable for use in many different relations in each of which there is present a tool which is of maximum efficiency.

While I have herein shown and described a preferred embodiment of the invention, it will be readily understood that changes and modifications therein may be found desirable or essential in meeting the various exigencies of use, and I desire to be understood as reserving the right to make any and all such changes and modifications as may be found desirable or necessary insofar as the same may fall within the spirit and scope of the invention as expressed in the accompanying 90 claims when broadly construed.

What I claim is:—

1. A tool holder comprising a casing, a tool holding element of less cross-sectional dimensions than the casing and adapted to be substantially housed thereby and shiftable axially thereof to permit tool introduction to and removal from the element, said element being adapted for use with either of a plurality of tools and adapted to have a generally similar mounting in the casing whether a tool is present or absent in the element, the casing and element having complementary cross-sectional configurations to limit introduction and removal of the element to such 100 axial direction and prevent relative rotative movement therebetween, and a cap freely movable relative to the casing and having a threaded engagement with an extension of said element, said cap and the tool receiving portion of the element being located at opposite ends of the casing, said casing having an internal stop arranged to be engaged by the inner end of the element to limit travel 105 of the element in one direction.

2. A tool holder as in claim 1, characterized by the fact that the casing element extension and stop are relatively formed to provide a chamber closed by the positioned cap and of dimensions to receive a plurality 110 of tools.

3. A tool holder as in claim 1, characterized by the fact that the stop is in the form of a fixedly positioned partition within the casing and formed with a central opening to 115

5 permit of the passage of the element extension, the casing and element extension having dimensions to produce a chamber therebetween with the partition forming the bottom and the cap a removable closure for the chamber, the dimensions of the chamber being such as to receive a plurality of tools.

6 4. In a tool assembly, a casing, a tool holding element and a tool, said element being 10 shiftable axially relative to the casing to permit positioning and removal of the tool, the element and casing having complementary configurations to prevent relative rotative movement of element and casing and to 15 limit the positioning and removal movements of the element to movement in the direction of length of the element, and complementary means on the element and tool to retain the tool in predetermined position in the assembly, said means including a longitudinal slot within and extending from an end of the element and having an enlargement of the slot within the element portion housed by the casing in the assembly, the tool having 20 cross-sectional dimensions substantially fitting the similar dimensions of the slot with one of the dimensions such as to permit its entrance within the casing with the element, said tool also having portions projecting on 25 opposite sides adapted to enter the slot enlargement, said casing having an internal stop adapted to be engaged by the inner end of the element portion.

30 5. A tool holder as in claim 4, characterized by the fact that the slot enlargement extends in the axis of the element, the projecting portions of the tool lying in a line transverse to the length of the tool.

35 6. In a tool assembly, a casing, a tool holding element and a tool, said element being shiftable axially relative to the casing to permit positioning and removal of the tool, the element and casing having complementary configurations to prevent relative rotative movement of element and casing and to 40 limit the positioning and removal movements of the element to movement in the direction of length of the element, and complementary means on the element and tool to retain the tool in predetermined position in the assembly, said means including a longitudinal slot within and extending from an end of the element and having a plurality of slot enlargements within the element portion housed by the casing in the assembly, the tool having 45 cross-sectional dimensions substantially fitting the similar dimensions of the slot and having portions projecting on opposite sides adapted to enter either of the slot enlargements, said slot enlargements including a longitudinal enlargement extending in the axis of the element, said enlargements being arranged and the complementary configuration of the tool being such 50 that the tool can be inserted only when a

corresponding length of the slot and an external entrance of an enlargement are both exposed.

55 7. A tool-holder as in claim 6, characterized by the fact that the axis of the longitudinal enlargement intersects the axis of another of the slot enlargements.

8. In combination, a tool holding element and a tool, said element being usable under service conditions as an element of and adapted to be housed within a tool holder or in independence of such holder, said tool-holding element having a non-circular cross-sectional contour and having means for positioning the tool therein detachably, said means including a longitudinal slot extending from one end of the element and having its side walls parallel, said walls being recessed to provide a slot enlargement extending in the axis of the element, said enlargement being operative to prevent tool movement relative to the element in directions other than in the direction of length of the enlargement, said tool having lateral projections lying in a line transverse to the length of the tool.

9. In tool holders, a tool holding element having means for positioning a tool therein detachably, said means including a longitudinal slot extending from one end of the element and having its side walls parallel, said walls being recessed to provide a plurality of slot enlargements having intersecting axes, with one of the enlargements extending in the direction of element axis.

10. A tool adapted for removable connection with a tool holder and having a flat body portion with opposing faces parallel, said body portion having means adjacent an end thereof for retaining the tool in operative position within the holder, said means comprising a formation projecting from each of such side faces said formation being of rivet-like characteristic with the heads of the rivet structures forming the projecting portion of the formation.

11. A tool as in claim 8, characterized by the fact that the projections are in the form of rivet-like structures secured to the body portion with the heads of the structures forming the projecting portions.

12. In a tool holder assembly, a casing, a tool holding element positionable relative to the casing by endwise movement, and a tool, said parts being relatively formed to permit assembly of tool and holding element while the latter is out of position, said tool and element being relatively formed to prevent relative movement therebetween in the direction of length of the tool while permitting such movement in a direction transverse to the length of the tool, said casing element and tool being relatively formed to permit positioning of the tool with its direction of length in corresponding

or in transverse relation to the general direction of length of the assembly.

13. In tool holder construction, a tool holding element and a tool removably connected, said element having an open-ended longitudinal slot to receive the tool, said element slot walls and the tool having complementary configurations to permit assembly of element and tool with the direction of

length of the tool extending either in correspondence with or transverse to the direction of length of the element, said configurations being operative to prevent withdrawal of the tool from assembly relation by movement in the direction of length of the tool. 10 15

In testimony whereof I affix my signature.

ANDREW ELIASON.
